BOW TIE AND METHOD OF MAKING SAME

Sol Head, New York, N. Y.

Application July 14, 1947, Serial No. 760,785

4 Claims. (Cl. 2—154)

1

This invention relates to improvements in decorative bows adaptable for wear on women's dresses, blouses and the like.

It is a general object of the invention to provide a decorative ready-made bow easily securable to and detachable from a garment at the neck portion thereof.

A further object of the invention is the provision of a decorative bow of the character described formed from a single length of material folded over at both ends about an intermediate portion and partially shaped to bow-like form by gathering together the central portion of the folded bow by means of wire stitching or the like to facilitate mass production of the article.

Another object of the invention is the provision of a decorative bow having adjustably secured thereto a fastening clip having pivoted fastening elements which open and close a pair of jaws for removably attaching the bow to a garment, each of said fastening elements being slidably engaged with a respective wing of the bow by wire stitching or the like to prevent damage to the material of the bow as the jaws of the fastening clip are repeatedly opened and closed with continual use.

The foregoing objects, as well as additional objects and advantages of the invention will be readily apparent in the course of the following detailed description taken in connection with the accompanying drawing which illustrates a preferred embodiment of the invention, and wherein:

Fig. 1 is a front view of a single length of substantially rectangular material from which the bow may be formed and which may comprise a length of lace mounted on a relatively heavy backing strip.

Fig. 2 is a rear view of the material of Fig. 1, showing the backing strip.

Fig. 3 is a perspective view illustrating the initial folding operation in folding the bow.

Fig. 4 is a front plan view of the finished bow.

Fig. 5 is a top plan view of the bow and its attached fastening clip.

Fig. 6 is a rear plan view of the bow and fastening clip showing the enlarged head of each fastening element concealed from view by insertion within a slit in the rear layer of the bow.

Fig. 7 is a similar view showing each fastening element of the fastening clip completely exposed alternatively to the procedure of Fig. 6.

Fig. 8 is a vertical sectional view taken through the central portion of the three layered bow before wire stapling.

Fig. 9 is a similar view showing the partially

2

formed bow after wire stapling the central portion thereof.

Fig. 10 is a similar view of the completed bow formed by securing a tie piece or ribbon about the central portion of the bow, the wire staple and the fastening clip being omitted for the sake of clarity.

The bow may be formed from any suitable material, but in the preferred embodiment of the invention, I employ lace mounted on a relatively heavy backing strip such as grosgrain ribbon or the like.

Referring to the drawing in greater detail, 10 designates the elongated rectangular strip which 15 may comprise a facing 11 of lace or the like and a relatively heavy backing 12, such as grosgrain. The ends of strip 10 may be trimmed with a binding 13 to prevent raveling and the ends are inwardly turned and stitched together to form the 20 points of the bow, as shown at 14.

The initial step in forming the bow is to fold each end portion of strip 10 about its central portion 10b, as shown in Fig. 3 to form a front layer 10a and a rear layer 10c continuously therewith with points 14 extending from each vertical fold line 15. The bow is then partially formed by folding or doubling over the three-layered, folded strip of Fig. 3 about its longitudinal axis at approximately the mid-point thereof, as shown 25 at 16, and securing this latter fold preferably by means of a wire stitch or staple 17 passing through the three doubled-over layers 10a, 10b and 10c.

A clip 18 of any desired conventional type is 30 used in order to removably secure the bow to a garment. In the preferred form, however, clip 18 comprises a pair of oppositely extending clamping jaws 19, each of which is actuated by an elongated pivoted lever or fastening element 20. Jaws 19 are opened when elements 20 are moved away from said jaws about their respective pivots and are closed when said elements are moved toward said jaws. Each element 20 is also formed with an enlarged head portion 21.

Clip 18 is preferably secured to the partially formed bow in the condition illustrated in Fig. 7 by passing a wire stitch or staple 22 about each element 20 and through the two inner layers 10b and 10c so as to conceal each staple 22 from view from the outside or front of the bow. Staples 22 also serve to maintain the configuration of the bow by securing together the inner layers 10b and 10c. In addition, the use of staples 22 achieves a flexible, slideable engagement of each element 20 with a respective wing 55

of the bow which is desirable because of the pivoted locking action of said elements. A distinct advantage is gained by this arrangement over conventional arrangements, using thread to fasten elements 20 or their equivalents, since tearing of the thread is eliminated and inadvertent separation between the clip 18 and the bow is prevented. The enlarged head portion 21 of each element 20 prevents said element from becoming disengaged from its respective wire staple 22.

After clip 18 has been secured to the bow in the above-described manner, the bow is completed by securing a tie-piece or ribbon 23 of any suitable material around the central portions of both the bow and the clip 18, as clearly shown in the drawings.

If desired, the enlarged head 21 of each element 20 may be concealed from view by forming vertical slits 24 in each wing of rear layer 10c adjacent to and outwardly of each staple 22 and inserting said head therewithin to be retained between rear layer 10c and intermediate layer 10b, as shown in Fig. 6.

Since certain modifications may be made in the article of the invention, without departing from the scope thereof, it is intended that all matter contained in the foregoing description and shown in the accompanying drawing be interpreted merely as illustrative and not in a limiting sense.

Having thus described my invention, what I claim as new and desire to secure by Letters Patent is:

1. A decorative bow removably securable to women's garments, said bow comprising an elongated strip of material folded at each end to define an outer layer, an intermediate layer and an inner layer, said bow being doubled over about its longitudinal axis at approximately the midpoint thereof, a wire staple passing completely through said doubled over layers closely adjacent the bight thereof to partially shape said bow, a clip including a pair of oppositely extending

fastening elements, additional wire staples extending transversely of said bow and located remote from said first-mentioned wire staple and slidably engaging said fastening elements against the inner layer of said bow and a tie-piece extending centrally around said bow and said clip.

5. A decorative bow removably securable to women's garments, said bow comprising an elongated strip of material folded at each end to define an outer layer, an intermediate layer and an inner layer, said bow being doubled over about its longitudinal axis at approximately the midpoint thereof, a wire staple passing completely through said doubled over layers closely adjacent the bight thereof to partially shape said bow, a clip including a pair of oppositely extending fastening elements, each of said elements having an enlarged terminal portion, a substantially vertical slit disposed near each end of said inner layer, each terminal portion of a respective fastening element being inserted with in a respective slit for concealment between said inner layer and said intermediate layer, an additional wire staple slidably engaging each fastening element against the inner layer of said bow and a tie-piece extending centrally around said bow adjacent a respective slit and said clip.

10. A decorative bow in accordance with claim 1, said elongated strip comprising a lace facing and a backing of relatively heavy material.

15. A decorative bow in accordance with claim 1, said elongated strip comprising a lace facing and a backing of relatively heavy material.

20. A decorative bow in accordance with claim 1, said elongated strip comprising a lace facing and a backing of relatively heavy material.

25. A decorative bow in accordance with claim 1, said elongated strip comprising a lace facing and a backing of relatively heavy material.

30. A decorative bow in accordance with claim 1, said elongated strip comprising a lace facing and a backing of relatively heavy material.

SOL HEAD.
